UNITED STATES PATENT OFFICE.

ANDOR RÓTH, OF NEW YORK, N. Y., ASSIGNOR OF ONE-HALF TO THEODORE FREUND,
OF NEW YORK, N. Y.

DOLL-HEAD.

1,146,596.

Specification of Letters Patent. Patented July 13, 1915.

Application filed February 4, 1915. Serial No. 6,119.

To all whom it may concern:

Be it known that I, ANDOR RÓTH, a subject of the King of Hungary, and a resident of the city of New York, in the county of 5 New York and State of New York, have invented certain new and useful Improvements in Doll-Heads, of which the following is a specification.

The present invention relates to doll heads, 10 and has for its main object to provide a device or mechanism for actuating the eyes or eye-balls of a doll to cause the same to roll or adjust themselves automatically, producing an action very similar to the movement 15 of the eyes of a natural person, said mechanism effecting also the closing and opening of the eyes as embodied in what are termed "sleeping dolls" now in common use.

Another object of the invention is to produce 20 a device of the character described which is simple in construction, efficient in operation, and which can be manufactured on a commercial scale, or in other words one that is not so difficult to produce as to be 25 beyond the reasonable cost of such an article.

A further object of the invention is to so construct the eye operating mechanism as to prevent binding of the eyes in the head of the doll.

With these and other objects in view, 30 which will more fully appear as the nature of the invention is better understood, the same consists in the combination, arrangement and construction of parts hereinafter 35 fully described, pointed out in the appended claim and illustrated in the accompanying drawings, it being understood that many changes may be made in the size and proportion of the several parts and details of 40 construction within the scope of the appended claim without departing from the spirit or sacrificing any of the advantages of the invention.

A few of the many possible embodiments 45 of the invention are illustrated in accompanying drawings, in which:

Figure 1 is a vertical sectional view of a doll head provided with the improved eye mechanism; Fig. 2 is a vertical section taken 50 through the same on a larger scale; Fig. 3 is a top plan view thereof, partly in section; Fig. 4 is a section taken on line 4-4 of Fig. 3; Fig. 5 is a vertical section taken through a modification of the invention; Fig. 6 is a

section taken on line 6-6 of Fig. 5; and Fig. 55 7 is a plan view, partly in section, of a further modification of the invention.

Referring now more particularly to Figs. 1 to 4, inclusive, the numeral 10 designates the hollow head of a doll, provided with 60 the usual eye apertures or openings 11. This head may be made of any suitable material, such as, for instance, bisque, wax or papier-mâché. In rear of the eye openings and in alinement with the same is oscillatably 65 mounted in the head a horizontally extending transverse shaft or spindle 12. This shaft is, preferably, mounted in bearing blocks 13 of wood or similar material, said blocks being held within recesses in the head. 70 The eyes or eye balls are denoted by the numeral 14. These balls are provided with horizontally extending recesses 15, which extend from the rear faces of said balls beyond the center thereof, and are adapted to ac- 75 commodate the shaft 12. The balls are drawn over the shaft and oscillatably held thereon by vertical pivot pins 16. In rear of the shaft is disposed a horizontally arranged connecting bar 17, its ends being located 80 within the recesses in the balls 14. This connecting bar is attached to the eye balls by vertical pivot pins 18. To the shaft 12 is centrally and fixedly attached a vertically 85 extending arm 19, the lower end of which bears, when the doll is in its upright position, against a stop 20 upon the inner face of the doll head. The upper end of said arm extends above the shaft 12, and has pivotally suspended therefrom a gravity-oper- 90 ated actuating member 21, such as a pendulum. The rod 22 of this pendulum extends through an opening 23 in the connecting bar 17.

The operation of this device is as follows: 95 When the doll is in its upright position, the pupils painted or otherwise represented upon the eye balls register with the eye openings, more particularly they are centrally arranged in relation to said eye open- 100 ings. When the doll is laid down, the pendulum causes the shaft 12 and thus the eyes attached thereto to swing around, or in other words it "closes the eyes". In handling the doll, as the head is shifted in its upright po- 105 sition from one position to another, the pendulum 21 swings by the intermediary of the connecting bar 17 the eyes around their pivot

pins 16, moving and adjusting the same simultaneously, and producing thus an action very similar to the movement of the eyes of a natural person. The arm 19 rests normally, that is to say when the doll is in its upright position, against the stop 20, and thereby keeps the eyes steady.

A modification of the invention is illustrated in Figs. 5 and 6 of the drawings, differing from the one above described in that the shaft or spindle 12 is provided with a downwardly extending substantially U-shaped bend 24, this bend bearing against the stop 20. The pendulum is attached in this case pivotally to an arm 25, said arm being attached to the U-shaped bend 24. The purpose of providing the shaft or spindle with a U-shaped bend is to impart to the same some resiliency. This structure will be particularly useful in connection with doll heads which are made of a material that shrinks to some extent after being thoroughly dried. By imparting resiliency to the shaft or spindle 12, the latter will not bind as the head shrinks.

In the modification shown in Fig. 7 of the drawings the eyes, denoted by the numeral 26, are substantially semi-globular. To these eyes are secured rearwardly extending horizontally disposed lugs 27, which are joined by a connecting bar 28, said bar being pivoted at 29 to the said lugs. The lugs extend also through the spindle or shaft 12, and are pivoted to the latter at 30. Otherwise the construction and operation of this device are in all respects identical with those of the

mechanism described in connection with Figs. 1 to 4, inclusive.

It is obvious that, while herein the invention has been illustrated in connection with a doll head, it is equally adapted for use in connection with toy puppets representing animals, etc.

What I claim is:—

A hollow doll head provided with eye apertures, a horizontal shaft oscillatably mounted within and transversely of said head, eye balls having horizontally disposed slots in their rear portions in which said shaft is seated, vertical pivot pins passing through said eye balls and said shaft, a connecting bar seated in the slots of said eye balls having a central opening, pivot pins passing through said eye balls and connecting bar, a vertical arm fixedly attached to said shaft and extending a substantial distance above and below the same, the lower end of said arm being adapted to bear against the inner face of said head and the upper end of said arm being provided with an eye, and a gravity operated actuating member suspended from the eye of said arm and extending through the opening in said connecting bar.

Signed at New York, in the county of New York, and State of New York, this 3rd day of Feb., A. D. 1915.

ANDOR RÓTH.
